UNITED STATES PATENT OFFICE.

LYNN M. TAYLOR, OF PEORIA, ILLINOIS, ASSIGNOR TO STANDARD OIL COMPANY, OF WHITING, INDIANA, AND CHICAGO, ILLINOIS, A CORPORATION OF INDIANA.

VALVE-OPERATING TOOL.

Application filed September 14, 1925. Serial No. 56,230.

To all whom it may concern:

Be it known that I, LYNN M. TAYLOR, a citizen of the United States, residing at Peoria, in the county of Peoria and State 5 of Illinois, have invented a new and useful Improvement in Valve-Operating Tools, of which the following is a specification.

My invention relates to a tool which I have more particularly devised for use in 10 operating valves in positions not readily accessible for hand-operation and especially such valves as are commonly provided on the crank-cases of motor-vehicle engines for the lubricant-draining purpose.

Having devised my tool for the especial use referred to, the following description thereof is confined to that connection.

In the accompanying drawing

Figure 1 is a broken view in side elevation showing the tool applied to a closed pet-cock, such as is provided on the crank-case of a motor-vehicle engine;

Figure 2 is a similar, enlarged view of the same, with the operating rod broken off, showing the tool applied to the pet-cock in its closed position.

Figure 3 is an enlarged view of the showing as regarded from the left-hand end of Fig. 1, and

Figure 4 is an enlarged perspective view of the tool with the operating rod broken off.

My primary object is to render the tool conveniently applicable to and releasable 35 from the valve when rotated to closed position, but non-releasable therefrom when open, thereby tending to induce closure of the valve against leakage after draining lubricant from the crank-case and replenishing it with fresh lubricant. This object 40 is accomplished by the illustrated construction of the tool, described as follows:

On one end of a suitable handle, in the preferred form shown of a rod 5 terminating at its opposite end in a ring 5^a, a socket 6, preferably of the rectangular shape shown, is secured. Claw-like hooks 6^a and 6^b are formed on two of the diagonally-opposite end-portions of the side-walls of 45 the hollow head or socket to extend in relatively opposite directions. Thus, with the pet-cock closed (that shown being of ordinary construction), when the expanded or thumb-piece end 8 of the valve-stem extends at right-angles between the discharge-

nipple 9^a and the inlet-nipple 9^b on relatively-opposite sides of the globular valve-casing 9, the socket 6 may be directed by the handle 5 to envelop and engage the end 8 of the valve-stem, whereby the hooks embrace the casing 9 between the nipples. By turning the handle 5 and with it the socket to rotate the valve into open position for emptying the crank-case, the hooks are brought to extend in relatively opposite 60 directions over the nipples 9^a and 9^b and thus obstruct withdrawal of the tool until it is turned to cause the socket to close the valve against leakage far enough to bring the hooks to their first-named position of 65 embracing the valve-casing, whereby the tool becomes released for withdrawal.

From the foregoing description it will be seen that I have provided an inexpensive, efficient tool for the purpose set forth and 70 one which is portable and which can be conveniently carried from one car to another in the operation of draining lubricant from the crank-cases of such cars and the replenishing of the same with fresh lubricant. 75

I realize that considerable variation is possible in the details of construction thus shown and described, and I do not intend to limit my invention thereto except as pointed out in the appended claims, by 80 which it is my intention to claim all the novelty inherent in my invention as broadly as permissible by the state of the art.

I claim:

1. A portable valve-operating tool comprising a socket-forming head provided with a handle and having hooks projecting in relatively opposite directions from diagonally-opposite parts of said head. 90

2. A portable valve-operating tool comprising a rectangular socket on one end of a handle-forming rod and having hooks projecting in relatively opposite directions from diagonally-opposite end-portions of the socket-sides. 95

3. A portable valve-operating tool comprising a socket on one end of a handle-forming rod and having rigid claw-like hooks projecting in relatively opposite directions from diagonally-opposite parts of the socket-walls. 100

4. A valve-operating tool having a socket-forming head adapted for connection with the operating member of a valve, and means carried by said head of such form as to 110

permit of the removal of the tool from the valve only when the valve is in closed position.

5. A valve-operating tool comprising a socket-forming head provided with a handle and having hooks projecting in relatively opposite directions from diagonally-opposite parts of said head, said socket be-

ing adapted to take over the operating member of a valve, and said hooks being so disposed relative to said operating member as to permit the removal of the socket from said member only when the valve is in closed position.

LYNN M. TAYLOR.
